UNITED STATES PATENT OFFICE.

ARTHUR FRIEDMAN, OF NEW YORK, N. Y.

SANITARY APPLIANCE.

Application filed September 25, 1925. Serial No. 58,563.

This invention relates to sanitary appliances and has for its object an appliance of the nature herein illustrated which can be worn with greater comfort, and applied with greater ease to the bodies of wearers differing in size, than can conventional articles of this character as constructed at present.

The various features of the invention are illustrated and described fully in the accompanying drawings and specification and pointed out in the claims.

In the drawings, Figure 1 shows in perspective a sanitary appliance in the construction of which this invention has been embodied.

Fig. 2 is a section thereof on the line II-II.

In the illustrated embodiment, the part 20 designated by the reference character 1 is a pad which may be of any suitable material and structure for the purpose, and which is illustrated as comprising an envelope or casing 2 of gauze or other penetrable fabric, enclosing a filler 3 of absorbent material with a layer 4 of non-absorbent material such as soft rubber sheeting interposed therebetween at the lower side of the pad.

30 The material of the envelope is extended beyond the front and rear of the portion containing the pad, and the rear extension 5 is provided with an elastic attaching member 6 stitched to the end of the extension 35 and adapted to pass around the waist of the wearer toward the front, having loops 7 at its ends.

The front extension 8 of the envelope has a tape 9, preferably of non-elastic material, 40 stitched across its end and the free portions of this tape are carried upward and passed through the loops 7 of the elastic tape 6, being adapted to be tied together adjustably in a bow-knot as shown at 10, so that 45 it affords means for attaching the appli-

ance easily and adjustably to the body of a wearer for different sizes of waist.

Preferably there are provided an additional tape or tapes 11 secured to the side margins of the envelope at intermediate 50 points 12, and passing beneath the envelope, the free ends thereof extending upward on each side of the body to the points of connection 13 with intermediate portions of the elastic waist tape 6. 55

Having described my invention, I claim:

1. A sanitary appliance comprising an elongated pad having an envelope with extensions at its ends, a tape secured to one of said extensions, and having its free ends 60 adapted to surround the waist of a wearer, said ends being provided with terminal loops, a tape secured to the other extension and having its free ends adapted to pass through said loops and to be tied, to tighten 65 said tapes respectively in place, and additional tape members secured at each side to said waist tape and extending downward therefrom toward, and attached to, said elongated envelope toward the rear of the 70 body of the wearer.

2. A sanitary appliance comprising an elongated pad, an envelope of fabric therefor, said envelope having extensions at its ends, an elastic tape secured to one of said 75 extensions and having its free ends adapted to surround the waist of a wearer, said ends being provided with terminal loops, a non-elastic tape secured to the other extension and having its free ends adapted to pass 80 through said loops and to be tied, to tighten said tapes respectively in place; and an additional tape passing beneath and secured to, said envelope, and connected with the intermediate portions of said elastic tape. 85

Signed at New York, in the county and State of New York, this 18th day of September, 1925.

ARTHUR FRIEDMAN.
